(57) **CLAIM**

The ornamental design for a container for drinks, as shown and described.

DESCRIPTION

The article is a plastic container, possibly for drinking water, which has a curved shoulder and a bellows barrel.

FIG. 1 is a front view of a container showing my design, with all other sides being identical;

FIG. 2 is a top view thereof;

FIG. 3 is a bottom plan view thereof;

FIG. 4 is a cross sectional view thereof in a collapsed condition; and,

FIG. 5 is a cross sectional view taken of sectional area 5 from FIG. 1.

1 Claim, 5 Drawing Sheets

FIG. 1

FIG. 2

FIG. 3

FIG. 4

FIG. 5
